UNITED STATES PATENT OFFICE.

WILLIAM L. DE REMER, OF CHICAGO, ILLINOIS.

TIE-PLATE.

No. 853,684.

Specification of Letters Patent.

Patented May 14, 1907.

Application filed August 25, 1906. Serial No. 332,064.

To all whom it may concern:

Be it known that I, WILLIAM L. DE REMER, a citizen of the United States, residing in Chicago, in the county of Cook and State 5 of Illinois, have invented certain new and useful Improvements in Tie-Plates, of which the following is a specification.

This invention relates to that class of tie-plates having a ribbed upper surface portion 10 and provided with a transverse reinforcing retaining rib on its under side adapted to be embedded in and extend transversely of a tie, so as to resist the side thrusts of the rail to which the plate is subjected in use. 15 In the art to which this invention relates, tie-plates are known which have corrugated upper surface portions and sharp bottom flanges which extend longitudinally of the ties or transversely with relation to the upper rail-engaging shoulder. Such longitudinal depending flanges add weight to the plate which it is very desirable to dispense with to as great an extent as possible without unduly diminishing the strength of the 20 plate. In other words it is very desirable to proportion and distribute the weight of the different parts of the plate to correspond as nearly as possible with the degree of stress and strains to which the respective parts are 25 subjected in use, so as to provide a plate having the minimum weight and maximum effectual strength.

The principal object of this invention therefore, is to provide a simple, economical and 30 efficient tie-plate.

Further objects are to provide a tie-plate formed of rolled steel and so constructed that the portions which are subjected to the greatest strains are efficiently reinforced and 35 proportionately heavy and strong, and the portions which are subjected to less strain are proportionately light, all parts having a strength substantially proportionate to the strain to which such parts are subjected, 40 whereby a plate of minimum weight and maximum effectual strength is formed.

A further object is to provide a plate having a substantially flat bottom face and a depending reinforcing rib so disposed as to resist the side thrusts on the outside of the rail and retain the plate in position upon the tie, 45 reinforcing the outer rail-engaging shoulder and the outer spike holes, such rib being adapted to be embedded in, and to extend 50 transversely with relation to the tie in such a

manner that the fibers thereof remain unbroken as far as possible.

Other and further objects of the invention will appear from an examination of the drawings and the following description and 55 claims.

The invention consists in the features, combinations and details of construction hereinafter described and claimed.

In the accompanying drawings Figure 1 is 65 a plan view of a tie-plate constructed in accordance with my improvements; Fig. 2, a view in elevation showing the bottom portion of a rail in position thereon, and Fig. 3, a sectional view in elevation taken on irregular 70 line 3 of Fig. 1, looking in the direction of the arrow and showing the relative positions of the upper rail-engaging shoulder and the depending retaining and reinforcing rib and outer spike holes.

In constructing a tie-plate in accordance with my improvements adapted to accomplish the above objects, I provide a main body portion *a* formed preferably of rolled steel and having an integral rail-engaging shoulder *b* upon its upper face adapted to extend along the outer side of, and in engagement with a rail *c* which may be of any ordinary and well known form. Inner spike holes *d* and outer spike holes *e* are provided 80 at suitable intervals upon opposite sides of the rail-supporting upper surface portion of the plate, and an integral reinforcing and retaining rib *f* extends along the bottom face of the plate parallel with the upper rail-engaging shoulder, in position to extend transversely to the tie and outside the outer edge of the rail when the plate is in operative position. The bottom reinforcing and retaining rib and the rail-engaging shoulder thus both 85 reinforce the outer spike holes and provide the greatest thickness of material and therefore the greatest strength at the points where the outer side of the rail rests, and where the side thrusts and the greatest strains are received.

The bottom surface of the plate is preferably flat with the reinforcing retaining rib projecting downward therefrom as described. This enables the plate to fit snugly against 90 the flat upper face of the tie so that it may have the greatest possible load-carrying capacity in proportion to its weight. The upper face of the plate is provided with rail-sustaining ribs *g* which extend obliquely 95

along the upper face of the plate at a preferably acute angle with relation to its longitudinal center. These upper ribs thus provide sufficient rigidity and strength both transversely and longitudinally of the plate and enable longitudinal depending flanges to be dispensed with. The upper rail-supporting ribs on each side of the plate extend preferably at an angle with relation to those at the opposite side so as to converge preferably toward the longitudinal center of the plate, or in other words so that their outer ends diverge.

The depending retaining rib is preferably of greater width than depth, and its bottom face extends from a point inside the outer spike holes to a point outside of the outer lower edge of the rail and also outside of the outer spike holes and the rail-engaging shoulder portion of the plate. The broad bottom face of the retaining rib, therefore, forms a load-supporting face and not a mere cutting edge, and is adapted to be embedded in the upper side of a tie without materially breaking or injuring the fibers of the wood. The plate thus retains substantially the advantages of a flat bottom plate, and yet the bottom retaining rib is adapted to reinforce the upper rail-retaining shoulder and to resist the shoulder thrusts on the outside of the rail. It thus increases and strengthens the adhesion of the plate to the tie without material injury to the fibers. The bottom rib also forms on all sides of the outer spike holes, reinforcing wall portions which are adapted to

engage all sides of the spikes below the upper surface of the tie when the plate is in position thereon. Rigidity and strength are thus added to both spikes and plate and the rigidity of connection between the plate and tie is increased. This form of depending retaining rib in combination with the oblique ribs and rail-engaging shoulder on the upper side of the plate enables the weight of the plate to be reduced to a minimum while retaining the maximum effectual strength and enables longitudinal depending flanges to be dispensed with without detriment to the plate and with benefit to the tie. The plate is rolled preferably longitudinally.

I claim:

1. A tie-plate provided with inner and outer spike-holes and a ribbed upper face portion, and having a retaining rib on its under side forming lower reinforcing wall portions below the plane of the main bottom face portion of the plate, on all sides of the outer spike-holes.
2. A tie-plate provided with ribs on its upper side extending at an angle to each other and obliquely with relation to the longitudinal center of the plate, and having a reinforced retaining rib on the under side of such plate adapted to extend transversely of a tie when the plate is in position.

WILLIAM L. DE REMER.
